United States Patent Office.

M. R. BARR AND WILLIAM T. BLACK, OF ERIE, PENNSYLVANIA.

Letters Patent No. 93,948, dated August 24, 1869.

IMPROVEMENT IN BASE-BURNING STOVES.

The Schedule referred to in these Letters Patent and making part of the same.

To all whom it may concern:

Be it known that we, M. R. BARR and WILLIAM T. BLACK, of Erie, in the county of Erie, and State of Pennsylvania, have invented a new and useful Improvement in Stoves; and we do hereby declare that the following is a full, clear, and exact description thereof, which will enable others skilled in the art to make and use the same, reference being had to the accompanying drawings, forming part of this specification.

This invention relates to an improved oven-attachment for base-burning stoves, and has for its object to provide an attachment under an arrangement calculated to be useful not only for baking, but for cooking in other ways, as frying, stewing, &c., and so that the heat shall pass directly under and around the exterior of the oven, or not, as required.

The drawing represents an elevation of a "Morning Glory" stove, partly in section, and provided with our improved oven-attachment, also sectioned.

At the rear of the cylinder enclosing the upper part of the heating-space, and where smoke-pipes are usually attached, we attach a double-walled oven, A, so arranged, relatively to the said cylinder, that one wall thereof occupies the place of or becomes the wall of the cylinder B, adjacent to the said ovens.

C represents an inclined flue leading from the shell of the stove at the top of the fire-pot to the bottom of the oven, between the two walls, a b, thereof, to convey the heat between the said walls up the sides and over the top of the escape-flue E.

F represents another passage, suitably separated from the passage C, and leading from the upper part of the heating-space up to the top and to the flue E.

G represents a double-acting damper, so arranged as to close the one passage and open the other simultaneously.

The inner wall of the bottom of the oven is provided with a pot-hole, H, wherein vessels may be set for cooking, and receive the direct action of the incandescent fire below, or the said hole may be covered when the oven is used for baking.

Having thus described our invention,

We claim as new, and desire to secure by Letters Patent—

The combination, with a base-burning stove, of an oven-attachment arranged therewith, so that the connecting-side of the oven forms a part of the shell of the stove, and having a flue, C, leading directly from the top of the fire, or one side thereof, to the bottom of the said oven; also having a hole, H, in the inner wall of the bottom, and a double-acting damper, G, all substantially as specified.
